(57) **CLAIM**

The ornamental design for solar powered house panel, as shown and described.

DESCRIPTION

FIG. 1 is a front perspective view of a solar powered house panel showing my new design;

FIG. 2 is a left side view thereof;

FIG. 3 is a right side view thereof;

FIG. 4 is a top plan view thereof;

FIG. 5 is a front view thereof;

FIG. 6 is a bottom plan view thereof; and,

FIG. 7 is a back view thereof.

This design is not limited to the exact details shown in the drawings, since equivalents and colorable imitations thereof will be evident to a person of ordinary skill in the art. Thus, within the scope of the appended claim, which is intended to cover only the ornamental and novel elements shown in the drawings, the invention may be practiced otherwise than as specifically shown and described herein.

The broken lines shown are for illustrative purposes and form no part of the claimed design.
